1

This invention relates to the control of motors used for driving machinery, and more particularly to those machines where two associated motors separately drive different parts of the same machine in such manner that the operation of one motor affects that of the other, as in the case of a service motor operating a device to which material is fed by a feed motor. In continuous screw presses, for example, a feed motor drives the screw of a hopper feeder unit which supplies material to the screw of an expeller unit driven by a second or service motor. Such presses are used for expressing liquid from a variety of substances, such as oil from corn germs, cottonseed, nut meats or other vegetable matter, or oil from cracklings or other animal matter.

Presses operating upon some of these materials, notably corn germs and cracklings, are subject to unexpected and rapid change in the fiber content, the word fiber being used here to denote the solid material remaining after the oil is expressed. When expressing corn germs, for example, mechanical difficulties in the separation of the corn germs from the kernels suddenly may cause the delivery to the press of a large quantity of whole corn kernels. Likewise, when expressing cracklings, the fiber content in the form of bone and bone fragments, suddenly may increase tremendously. The expeller operates on a setting of the choke based upon a definite average fiber content and chosen to produce maximum output and the desired efficiency in extraction with both motors loaded to their rated capacities.

In either of the cases mentioned above, when the fiber content of the material suddenly increases, the motors, or one of them, may become overloaded. Usually the hopper feeder motor is overloaded first and stops by operation of its overload relays. But the service motor which operates the expeller, which has not yet felt the effect of the increased duty, keeps on operating and may completely empty its barrel or unload its screw within a matter of a few seconds to a couple of minutes. Consequently all resistance to advance of the material disappears by reason of loss of the plug at the choke. When the overload condition is detected and the operator restarts the feed motor, it may take from ten to fifteen minutes to again build up a plug and thus produce the necessary back pressure at the choke in order to again secure maximum capacity and efficiency in the extraction of oil or grease.

On the other hand, should the expeller motor begin to overload for any reason, such as an in-

flux from the hopper feeder too large or too rapid for the expeller to handle, it is desirable temporarily to stop the hopper feeder motor until the expeller catches up and its load drops back to normal.

The present invention has for its object to overcome this loss of time and efficiency by the provision of an improved automatic control system, requiring no special attention by an operator, which promptly restarts the hopper feeder motor, should it stop, at least early enough to avoid or prevent such loss of back pressure or resistance to advance of the material in the expeller as might reduce or impair efficiency, and in cases where the expeller motor is overloading, as soon as its load returns to normal. Restarting of the hopper feeder motor takes place after a time interval which is relatively short, but still is sufficient to insure such reduction in load upon the expeller motor as will enable its screw to clear away some of the material in the expeller ahead of the hopper feeder and provide room or space into which the hopper feeder screw can relieve itself. The short time interval may be either a predetermined definite period, time controlled, or may be a variable period dependent upon varying conditions, as will appear.

Another object is to provide a control system of the character described in which upon stopping of one of two associated driver motors, the stopped motor is restarted by means rendered effective upon or by the deenergization of one of its circuits, either operating or controlling.

Still another object is to control restarting of the stopped motor by means rendered operative or effective upon reduction in the load upon the motor which continues in operation.

Finally, another object is to control restarting of a stopped motor by means sensitive to an overload upon it, thus dispensing with operator control for the purpose.

Further objects of the invention in part are obvious and in part will appear more in detail hereinafter.

45 In the drawings,

Fig. 1 represents, partly in section and partly in elevation, one form of press embodying the invention;

Fig. 2 is a diagram, illustrating one arrangement of the controlling circuits; and

Figs. 3, 4 and 5 are similar diagrams, showing other arrangements.

While the invention is capable of use for the control of any motor, or for any machine or device actuated or driven by two associated motors

where the load of one depends upon the duty of the other, for any reason, the drawings, solely for purposes of illustration and in no sense of limitation, show the invention applied for use in the control of the driving motors for a continuous screw press. The press chosen for illustration is of a common type, such as is used for expressing or expelling oil or other liquid from any solid material, either vegetable or animal, such as the materials before referred to. It includes a cooking vessel or conditioner 10 from which the material to be pressed is delivered to a hopper feeder unit 11, by means of which it is fed or delivered to an expeller unit 12.

The hopper feeder unit includes a perforate barrel 13 in which rotates a screw 14 driven by feed motor 15.

Similarly, the expeller unit includes a perforate barrel 16 in which rotates a screw 17 driven by the expeller or service motor 18.

The axis of the hopper feeder screw 14 is vertical and the axis of the expeller screw 17 is horizontal. The hopper feeder element accepts the material delivered to it by the conditioner and forces it downwardly at gradually increasing pressure into the chamber of the expeller unit. During its travel downwardly through the hopper feeder the material undergoes some compression and extraction, oil escaping through the orifices of the perforate barrel.

The expressing operation is completed in the expeller unit, where the pressure applied to the material gradually increases to a maximum at the discharge end, where the material passes through the usual adjustable choke 19.

In a continuous press of this kind, maximum efficiency, as regards expulsion of oil or other liquid from the material being operated upon, is secured by proper adjustment of the choke so as to more or less restrict the outflow and apply resistance to advance of the material to the discharge. Proper restriction of the choke builds up back pressure resisting advance of the material in the second or expeller element, a resistance which is reflected back into the hopper feeder element so as to build up the pressure, but of course a lesser pressure, in that element, clear back to the inlet where the material enters from the conditioner.

In the operation of these presses the two motors are of course provided with overload relays or safety devices. When the expeller motor actually stops for any reason, as by actuation of its overload limit relay, an additional load or resistance of course is thrown back upon the hopper feeder element and its motor, the latter of which stops in due course because of overload. With such an extreme condition, or that kind of motor stopping, the present invention is not concerned. Such stoppage of both motors requires correction and restarting, usually by manual control, in the usual manner with presses of this kind.

According to the present invention, means is provided, in the control system for the motors, to take care of cases when the hopper feeder motor stops, as by reason of the sudden inflow to it of a quantity of material having an abnormally high percentage of fiber content, such as in the case of corn germs and cracklings as mentioned above, or cases where the expeller motor begins to overload, but to a value short of that which stops it by actuation of its overload limit switch. The restarting means for the hopper feeder motor may be of any suitable form, and operated or controlled by any suitable means, so long as it

is sensitive to or set into operation by an abnormal or unusual increase in the fiber content (as above explained) of the work, and produces a restarting operation or effect after the lapse of a reasonably short period of time, a period not so long as to reduce the load on the expeller to a value where substantially all resistance or back pressure of the work is lost, but nevertheless long enough to permit such operation of the expeller as will partially unload it, with reduction of its motor load toward but not below a predetermined minimum value. A control system suitable for this purpose is shown in Fig. 2 of the drawings.

In Fig. 2, A represents the starting control panel; B the starting box or panel for the expeller motor, conventionally shown at 18; C a similar starting box or panel for the hopper feeder motor, shown conventionally at 15; and D a panel or subpanel for a time delay relay, to be described.

On the starting panel A are located a normally open starting switch S₁, a normally closed stop switch S₂ and an ammeter 20, all for the expeller motor, and also a normally open starting switch S₃, a normally closed stop switch S₆ and an ammeter 21, all for the hopper feeder motor 15.

On the starting panel B are located a normally open main switch S₃ including three blades in circuit conductors 22, 23, 24 from the current leads L₁, L₂, L₃, said switch being actuated by a coil 25 which also operates normally open maintaining switch S₄. One of the leads, as 22, includes the primary 26, of a transformer, the secondary 26a of which is in circuit through the conductors 21, 28 with ammeter 20. Each of the other two conductors as 23, 24, includes a coil 29 for actuating one or the other of two normally closed overload limit relay switches S₁₀, S₁₁, of ordinary form arranged to close immediately after opening.

The starting panel C for the hopper feeder motor includes a similar three-blade main switch S₉, the blades of which are in the conductors 30, 31, 32 to hopper feeder motor 15 from the leads L₁, L₂, L₃, said main switch being actuated by coil 33, corresponding to coil 25, said coil also actuating the blades of a normally open maintaining switch S₇ and a normally closed switch S₈. The blades of switches S₇, S₈ are so harnessed together or arranged that in operation switch S₈ opens after switch S₇ closes, and vice versa. One conductor 30 includes the primary 35 of a transformer, the secondary 35a of which is in circuit with ammeter 21. The other two conductors 31, 32 each include a coil 34 for actuating one or the other of the overload limit relay switches S₁₂, S₁₃, corresponding to switches S₁₀, S₁₁.

On the panel D is located a time delay relay, conventionally shown at 36 and arranged to actuate the blade of switch S₁₄, later to be referred to.

With the arrangement described, and as shown in Fig. 2, assuming both motors at rest and all switches and other devices in the normal positions shown, it is impossible to start the hopper feeder motor until the expeller motor has first been started. The reason is that no lead line to the starting switch S₅ is alive. Consequently it is necessary to first start the expeller motor. This is accomplished by closing its starting switch S₁, completing a circuit from L₁, by way of conductor 22, conductor 37, starting switch S₁, now closed, stop switch S₂, conductor 38, overload relay switches S₁₁, S₁₀, coil 25, conductor 39 and con-

ductor 24 to L₁, thus energizing coil 25. This promptly closes not only the main switch S₃, thus energizing the expeller motor, but also maintaining switch S₄, thus establishing a maintaining circuit from L₁ by way of wire 40, switch S₄, now closed, conductor 41, conductor 42, and then through stop switch S₂ and wire 38 and coil 25 back to L₂ as before. It is now possible to remove the finger from the start button and still maintain the main switch S₃ closed and thus keep motor 18 in operation.

It is now possible to start the hopper feeder motor by closing its start button S₅, with results as follows:

Current flows from L₁ by way of conductor 40, switch S₄, conductor 41, conductor 42, conductor 43, start switch S₅, now closed, stop switch S₆, conductor 44, overload relay switches S₁₃, S₁₂, coil 33, conductor 45 and conductor 46 to L₂.

Energyization of coil 33 promptly closes main switch S₉, thus completing the circuit through the leads 30, 31, 32 to motor 15 and starting the same, and also closing switch S₇ and immediately after closing of that switch, opening switch S₈.

Switch S₁₅ is now closed manually to prepare the time delay relay 36. Switch S₁₅, it should be stated, is a manually operated switch stable in either open or closed position. When said switch is open, the automatic control being described is ineffective, and the hopper feeder motor must be started by manual control in the manner before described. When said switch is closed the automatic restarting mechanism is effective.

On panel C the bridging wire 40, shown in dotted lines and corresponding to the same numbered wire on panel B, is omitted, and the corresponding contact of switch S₇ is connected by a conductor 47 and conductor 42 to the conductor 41 of the corresponding switch on panel B. The other contact of switch S₇ is connected by a conductor 48 to a contact of switch S₁₄, the other contact of which is connected by conductor 49 to conductor 42 and the other contact of switch S₇.

Closing of switch S₇ creates a maintaining circuit for the coil 33, corresponding to that for coil 25 before described, and including conductors 44 and 54, and stop switch S₁, while opening of switch S₈ opens the circuit through conductors 50 and 51 to the time delay relay 36.

The press is now in operation with the various switches occupying the new positions described, both motors operating up to rated capacity, as determined by motor design and as controlled by the overload limit relay switches S₁₀ to S₁₃ inclusive.

If, now, for any reason, the hopper feeder motor suffers a sudden or abnormal increase in load, such as on account of a sudden increase in the fiber content of the material being delivered to the hopper feeder screw, one or the other of the coils 34 on the hopper feeder motor control panel will actuate and open its switch S₁₂ or S₁₃, or both. This deenergizes coil 33, permitting main switch S₉ to promptly open, and causing switch S₇ to open, followed promptly by closing of switch S₈.

Thereupon the circuit to the time delay relay 36 is closed, current flowing as follows: From L₁ by conductors 22 and 40, switch S₄ (still closed), conductor 41, conductor 42 to the point 52, switch S₂ (now closed), conductor 50, switch S₁₅ (assumed to be closed), the coil of time delay relay 36, conductor 51, conductor 45, conductor 46 to L₂.

Continuing, when the time delay relay is energized it goes through its usual operation and

at the end of any suitable period for which the relay is adjusted, say anywhere from five or ten seconds up to two minutes or more, said relay closes the switch S₁₄. This switch completes a circuit as follows: From L₁, by way of conductors 22 and 40, switch S₄, conductors 41, 42, conductor 49, switch S₁₄, conductor 48, conductor 54, stop switch S₆, conductor 55, overload relay switches S₁₃, S₁₂, coil 33, and conductors 45, 46 to L₂. The effect is to energize coil 33 and produce a starting operation of motor 15 by closing of the main switch S₉ as before, together with closing of switch S₇ and subsequent opening of switch S₈, to establish a maintaining circuit for the coil 33, as before.

The parts have now been restored to their operating positions, with both motors operating as before. During the time delay period, whatever it may have been, when the hopper feeder motor is at rest, the expeller motor continues in operation. Of course, the load upon said motor gradually decreases as the expeller gets out of the way some of the material undergoing extraction in the expeller element, relieving the back pressure on the hopper feeder element and providing space into which it can discharge its overload of abnormal fiber content, when it is restarted.

In the form of invention just described, restarting of the stopped hopper feeder motor of course is sensitive to or set in operation by an increase in the load upon the hopper feeder motor, as reflected into the control system by the overload relay switch S₁₂ or S₁₃. Two effects are produced by the overload, first, stopping of the hopper feeder motor, and, second, energization of the time delay relay 36 to produce restarting after the lapse of a predetermined definite period in accordance with the setting of the time delay relay. In this arrangement, therefore, the hopper feeder motor is always restarted after the lapse of a predetermined definite period, during which the load on the expeller motor drops.

Under some circumstances it may be desirable to restart the hopper feeder motor after the lapse of a period of time which is more or less variable and which depends upon some other controlling factor. For example, the delay period may be of undetermined value but rendered definite in accordance with reduction in the load upon the still running expeller motor. Such an arrangement is illustrated in Fig. 3, now to be described.

This arrangement does not require extended description, since most of the circuits and parts are identical in construction, arrangement and manner of operation with those illustrated and described in connection with Fig. 2. For this purpose, the more important like parts and circuits, in the two views, have been identified with like reference characters, so that detailed description thereof may be omitted. The differences between the two arrangements are as follows:

Restarting of the hopper feeder motor in this instance is produced by closing of a normally open switch S₁₆, the conductors 60, 61, for which are connected respectively to the same conductors 42, 44 before described. Switch S₁₆ is mounted upon a panel E. Its movable blade is connected to an armature 62 actuated by a coil 63 in a circuit, the conductors 64, 65 of which are connected to the secondary 66 of a current transformer, the primary 67 of which is in one of the lead wires, such as 23, of the expeller motor circuit.

With this arrangement the system is set into

operation in the manner before described, by successively closing the normally open start switches S_1 , S_5 , thereby first starting the expeller circuit and energizing its maintaining coil 25 , and establishing a maintaining circuit therefor, and then starting the hopper feeder motor by similarly energizing its maintaining coil 33 and establishing a corresponding maintaining circuit therefor. Whenever the hopper feeder motor stops, for one of the reasons before described, such as a sudden influx of material of abnormally high fiber content, one or both of the overload switches S_{12} , S_{13} opens, as before, deenergizes coil 33 , and permits the main switch S_9 to open, stopping the hopper feeder motor. The expeller motor continues to run, however, for a relatively short period of time, sufficient to enable it to clear away some of the material in the expeller element, preparatory to restarting the hopper feeder unit. The length of the time period here depends upon reduction in the load upon the expeller motor to a definite low value, instead of an indefinite value, as before described.

The current transformer 66 , 67 , and the parts of the switch controlling relay 62 , 63 , are so constructed and arranged that normally, when the expeller motor is operating at rated capacity, or at any load above a predetermined value, sufficient current flows in the circuit 64 , 65 to maintain the armature or plunger 62 in its switch-open position. But as the duty of or load upon the expeller motor decreases, the current flow in said circuit decreases until finally it is not sufficient to hold the plunger 62 , which thereupon moves over to its other position, closing switch S_{16} . Closing of switch S_{16} energizes a circuit (Fig. 3) as follows: From L_1 by way of conductors 22 , 40 , maintaining switch S_4 of the expeller motor circuit, still closed, conductor 41 , conductor 42 , conductor 68 , switch S_{16} , now closed, conductor 61 , manually operable switch S_{15} (corresponding to and for the same purpose as switch S_{15} of Fig. 2) conductor 44 , overload relay switches S_{13} , S_{12} , maintaining coil 33 , conductor 45 , and conductor 46 to L_3 .

The effect of closing this circuit is to reenergize coil 33 , close main switch S_9 for the hopper feeder motor, and energize its circuits to start said motor.

This arrangement, therefore, not only automatically restarts the hopper feeder motor, whenever it stops for the reason stated, and thus tends to keep the machine in operation without special attention by the operator, but it also provides a variable time delay period self-adjusting, as it were, to the nature of the particular material which has caused motor stoppage, in the sense that restarting of the hopper feeder motor depends upon definite reduction in load upon the expeller motor consequent upon stopping.

With this circuit, the expeller motor therefore can be kept at load automatically, based upon the load on the hopper feeder motor.

Preferably the relay 62 , 63 is adjustable in any suitable manner to vary the number of amperes, or the load, desirably carried as a minimum on the expeller motor, or in other words, the load to which this control relay is responsive. The drawings (Fig. 3) show switch S_{16} as a conventional snap switch, held in either open or closed position by the yielding button 68 , and moved toward closed position by the weight of armature 62 and the tension of loading spring 69 adjustable by screw 70 , and toward open position by the pull of coil 63 . By adjustment of screw

70, the relay may be made to yield and permit closing of switch S_{16} at any desired motor load, thus adapting the system to variations in material being pressed, or other changing conditions. This adjustment might be made once a month, or even oftener.

In both forms so far described, of course, the overload limit relay switches S_{10} , S_{11} , S_{12} , S_{13} are of a usual or well-known form, opening momentarily upon increase in load to a predetermined limit, adjustable to respond to any desired limit value of overload, like relay switch S_{16} , and arranged to close promptly, after a short time interval capable of variation by suitable adjustment, when the motor circuit is opened, ready for another operation.

The systems so far described automatically take care of any condition in which variation in the fiber content of the material causes stopping of the hopper feeder motor, restarting said motor automatically after a suitable time delay period, by means which is rendered effective upon or by deenergization of the hopper feeder motor circuit, or upon reduction in load upon the expeller motor consequent upon or caused by deenergization of the hopper feeder motor.

However, the invention is not limited to control by stopping or overload of the hopper feeder motor circuit, but is equally applicable when the condition requiring correction is an increasing overload in the expeller motor circuit. A control system thus functioning is shown in Fig. 4.

In Fig. 4 all parts and circuits are the same as those in Fig. 3, with exceptions, as follows:

35 Here the maintaining circuit for the hopper feeder motor includes an overload switch S_{17} and its operating coil 71 , similar in all respects to switches S_{10} , S_{11} , etc., and their coils, and likewise adjustable as to load response and time interval in closing. The maintaining circuit extends from L_1 , by conductors 22 , 40 , switch S_4 , conductor 41 , conductor 42 , switch S_7 , conductor 54 , switch S_{17} , stop switch S_6 , conductor 44 , switches S_{13} , S_{12} , coil 33 , conductors 45 , 46 to L_3 .

45 Should the expeller motor circuit become overloaded, to the degree for which coil 71 has been adjusted or set, switch S_{17} opens, thus deenergizing coil 33 and opening the main switch S_9 and stopping the hopper feeder motor. Of course the critical load to which switch 17 responds is less than that to which switches S_{10} , S_{11} respond. The consequence is exactly the same as before described, to wit, a gradual reduction in load upon the expeller motor until, finally, switch S_{16} is closed by the effect upon coils 66 , 63 , with consequent restarting of the hopper feeder motor, as before.

Fig. 5 shows still another arrangement for the same general purpose. Here another lead 24 to the expeller motor includes the coil 72 of a relay on panel F, the switch S_{18} of which again is included in the conductor 54 of the maintaining circuit for the hopper feeder motor. This relay may be of the same type and arrangement as those marked S_{10} , S_{12} , etc., and before described, but, of course, set to operate at a lower value of overload. Here again, an overload upon the expeller motor stops the hopper feeder motor and initiates a restarting operation therefor, dependent upon reduction in load upon the expeller motor, or, if the system of Fig. 1 is employed, upon the lapse of a definite time period.

The systems described supply full protection for two types of conditions, requiring control, one, where overload occurs in the hopper feeder mo-

tor circuit, and, two, where it occurs in the expeller motor circuit.

In either case, the condition is corrected by stopping the hopper feeder motor and then starting it again, after overload has passed, by time delay for a suitable period, determined either by a timing device or by means sensitive or responsive to reduction in the expeller motor load. In the first case but one relay is required, while the second requires two, one to stop the hopper feeder motor and the other to restart it. Either system is satisfactory.

Other advantages of the invention will be apparent to those skilled in the art.

What I claim is:

1. Control means for a motor system which includes a service motor and a feed motor cooperating therewith and provided with a starting and maintaining circuit, comprising an overload relay in the feed motor circuit, means responsive to said overload relay for opening the feed motor circuit and stopping the feed motor when overloaded, and means rendered effective by thus opening the feed motor circuit and effective upon reduction in load upon the service motor to thereby close the feed motor circuit and restart the feed motor.

2. Control means for a motor system which includes a service motor and a feed motor cooperating therewith and provided with a starting and maintaining circuit, comprising an overload relay in the feed motor circuit, means responsive to said overload relay for opening the feed motor circuit and stopping the feed motor when overloaded, and

time delay means rendered effective by thus opening the feed motor circuit and after the lapse of a period sufficient to reduce the load upon the service motor to close the same and restart the feed motor.

3. Control means for a motor system which includes a service motor and a feed motor cooperating therewith and provided with a starting and maintaining circuit, comprising an overload relay in the feed motor circuit, means responsive to said overload relay for opening the feed motor circuit and stopping the feed motor when overloaded, and means rendered effective by thus opening the feed motor circuit and responsive to predetermined reduction in load upon the service motor and thereby effective upon the feed motor circuit to close the same and thus restart the feed motor.

RAYMOND T. ANDERSON.
